CLAIM

The ornamental design for a suction container, as shown and described.

DESCRIPTION

FIG. 1 is a perspective view of a suction container in a first position;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof;

FIG. 8 is a perspective view of the suction container in a second position;

FIG. 9 is a top plan view thereof;

FIG. 10 is a bottom plan view thereof;

FIG. 11 is a left side elevational view thereof;

FIG. 12 is a right side elevational view thereof;

FIG. 13 is a front elevational view thereof; and,

FIG. 14 is a rear elevational view thereof.

The broken line portions of the suction container represent unclaimed portions of the claimed design and form no part thereof.

1 Claim, 14 Drawing Sheets
